THERMIONIC DISCHARGE DEVICE

Forrest E. Gehrke, Flushing, N. Y., assignor to
Sylvania Electric Products Inc., a corporation
of Massachusetts

Application July 1, 1948, Serial No. 36,333

11 Claims. (Cl. 250—27.5)

1

The present invention relates to thermionic discharge devices and more particularly to gas discharge devices depending, for their operation, upon ionization of the contained gas.

An object of the present invention is the improvement of the construction and operation of grid controlled gas discharge devices.

Another object of the present invention is the provision of a simplified shield grid assembly for a shield grid gas discharge tube.

A further object of the present invention is the provision of forms of control grid and shield grid construction for use in grid controlled gas discharge tubes such that they may be stamped out of strip material as a finished part and thus not require further assembling operations.

Still another object of the present invention is the provision of a grid controlled gas discharge tube in which large variations in dimensions of the parts of the tube have little effect on the operating characteristics of the tube.

Still a further object of the present invention is the provision of a grid controlled gas discharge tube which is tolerant of misalignment of parts during assembly.

Still a further object of the present invention is the construction of a grid controlled gas discharge tube which is uniform in its characteristics and which maintains these characteristics throughout its life.

Still another object of the present invention is the provision of a grid controlled gas discharge tube in which the effect of cathode contamination is minimized.

The foregoing objects, and others which may appear from the following detailed description, are attained by providing within an hermetically sealed casing containing an ionizable gas, a tetrode assembly including a heated cathode, a control grid, a shield grid, and an anode. The shield grid and control grid are so designed that they can be made as unitary parts of strip material on high speed stamping and forming machinery.

The arrangement of the control grid surfaces with respect to the shield grid assembly is such as to prevent crowding of equipotential lines in the space between the anode and cathode. Furthermore, the control grid is so arranged that the surfaces of the grid are hidden from the cathode and from the plate, thus providing a very low grid-to-anode capacitance and grid-to-cathode capacitance.

In an embodiment of the present invention the shield grid is preferably formed generally

2

in somewhat the shape of an hour glass or a lemniscate having a constricted passage between its loops. Within the central neck portion of the shield grid assembly is arranged the control grid, which is in the form of a flat loop of strip material. The cathode is arranged in one of the enlarged end spaces of the shield grid and the anode in the other.

The present invention will be more fully understood by reference to the following detailed description, which is accompanied by a drawing in which:

Fig. 1 illustrates, in elevation and partly in section, a tube embodying principles of the present invention, while

Fig. 2 is a transverse cross-section of the tube shown in Fig. 1 taken along the lines 2—2 of Fig. 1;

Fig. 3 is a plot of the electrostatic field within the tube of Figs. 1 and 2, while

Fig. 4 is a similar plot of the electrostatic field in certain prior art tubes, with which I am familiar, and

Fig. 5 is a schematic circuit diagram showing the relationships of the various elements within the tube of the present invention and their consequent inter-element capacity effects.

In Fig. 1 is shown a thermionic discharge tube having an hermetically sealed glass envelope 10 containing an ionizable gas such as argon, mercury vapor or helium. (Other gases may be used if desired.) Within the tube envelope is arranged a tetrode thermionic discharge assembly including a cathode 12, a control grid 14, an anode 16, and a shield grid or shield 18. The tetrode parts are maintained in their relative position within the glass envelope 10 by being secured to mica spacers 19 and 20.

In a preferred form of construction, the cathode is in the form of a hollow tube having a heater element, not shown, therewithin, and an electron emissive coating on the exterior, is maintained in position by being snugly fitted through holes in the mica spacers 19 and 20. The grid 14 is formed of flat sheet stock bent over on itself and slightly spread apart in its intermediate portions to form an open loop in the region between spacers 19 and 20. The end portions 23 and 24 are flattened together to pass through flat slots in the mica. Anode 16 is preferably secured in place by curved ears 25 and 26 extending through arcuately shaped apertures in the spacers 19 and 20. Shield grid 18 may be similarly secured in place, or, as shown in the present drawing, support rods 28 passing through the mica end

spacers and spot welded to the shield grid 18 may be used.

Connections to the various elements within the evacuated envelope 10 are provided by means of leads 29 passing through the button base 30 of the envelope. In the present tube there are provided six connection leads 29, one pair for the heater, one lead for the cathode 12, one for the control grid 14, and one each for the anode 16 and shield grid 18.

As may be seen by reference to Fig. 2, the shield grid 18 is generally of hour glass formation having the control grid 14 in the neck portion of the hour glass, and the cathode 12 and anode 16 each in one of the enlarged portions of the shield grid.

In order to facilitate processing the tube, it is desirable to provide a narrow window or aperture 31 in the shield grid directly behind the anode 16. Anode 16, however, entirely covers the window so no stray electron streams from the cathode are able to emerge through the window 31.

In Fig. 3 I have shown, schematically, the same general arrangement of electrodes as shown in the cross-section in Fig. 2, but have added a number of dotted lines 40 indicating equipotential lines between the cathode 12 and the anode 16. It will be noted in Fig. 3 that the equipotential lines 40 are not crowded at any point, but rather follow smoothly flowing contours. Crowding of the equipotential lines indicates high potential gradients. Since it is the potential gradients along an electron stream that effect the direction and velocity of the electrons in the stream, it may be seen that the slightest variation in dimensions of the opening of a grid, having a point or thin line as the active element, may have very large effects upon the tube's performance and upon uniformity of characteristics between different tubes of the same type. In the present arrangement the reverse is true, thus, large variations in spacing and dimensioning may occur without seriously effecting the potential gradients through which any electron passes at a given point. This situation may be contrasted with the arrangement shown in Fig. 4 wherein the equipotential lines are indicated in a prior known form of shield grid thyatron. Here plates 50 and 51 constitute a part of a shield grid assembly. They may be associated with a surrounding box-like cage. It should be carefully noted that the equipotential lines 52 in Fig. 4 are extremely cramped and close together where they pass through the apertures in plates 50 and 51. Thus, very slight variations in dimensions, or in positioning of the elements, may cause a substantial variation in characteristics of tubes constructed in this manner.

Again referring to Fig. 3, it will be noticed that the control grid 14 is well hidden from the cathode 12, thus keeping the capacity between the control grid and cathode at a minimum. Also, cathode coating, which may be sputtered off cathode 12, through its life, will not tend to deposit on control grid 14. Such action is a usual source of drift during life of the control grid firing characteristic of prior art tubes.

Furthermore, the present invention avoids non-uniformity of operation due to electron emission from the control grid 14 brought about by photons liberated from cathode 12 because the control grid surfaces, i. e., the flat faces of control grid 14, are hidden from cathode 12 to a great extent by the shield grid assembly. Thus, photons liberated from the cathode 12 do not strike the active surfaces of the control grid 14 to cause secondary

emission. Next, it will be noted, that the control grid 14, or at least its control surfaces, is well hidden away from the plate 16, thus resulting in a thyratron which has a very low grid to anode capacitance. This is of considerable importance in preventing interaction between voltages appearing at the anode and grid. Ordinarily it is highly desirable that these be substantially independent of each other, except as coupled by the operating characteristics of the tube. The way in which capacitive interaction may occur between the grid and cathode is shown in the circuit of Fig. 5. Many gas discharge tube applications concern uses in which the grid circuit is placed in an extremely high impedance circuit, of the order of ten megohms or higher, such as that indicated at 60. This occurs because it is expected of a gas discharge tube that it will be able to control large amounts of anode current through the application of very minute currents to the grid circuit. If the control grid-cathode capacitance C_{gk} is high, the reaction time of the controlling circuit, or grid circuit, is high because the capacitor C_{gk} must be charged up first through the high impedance of the grid circuit.

If the control grid-anode capacity C_{gp} is high, the relatively long time needed for the high impedance in the grid circuit to discharge this capacitor will prevent the controlling circuit from operating correctly, if, in fact, it has any control at all. Due to the fact that the control grid 14 presents only its edge surfaces to the cathode 12 and the anode 16, the interelectrode capacities C_{gk} and C_{gp} are small, and the deleterious effects described above are avoided.

Furthermore, the shield grid 18 substantially completely encloses the structure allowing no free openings where the electron stream from the cathode 12 may emerge to impinge upon the glass walls. The effect of such impingement is the release of contaminating vapors and gases which adversely affects the operation and life of the tube.

It will be seen that the present improved design of a grid control gas discharge tube provides improved operating characteristics and a simpler arrangement of electrodes without sacrificing anything towards its mass producibility and low cost. Furthermore, tests indicate that good uniformity between several tubes of the same type is obtained and life performance tests have appeared to be substantially better than prior art construction even though the particular tubes tested were operated with an extremely low heater input compared to that used with heretofore available indirectly heated cathode-grid controlled gas discharge tubes.

While I have shown and particularly described a preferred embodiment of the present invention, it is to be clearly understood that the present invention is not limited thereto, but that modifications within the scope of the invention may be made.

What is claimed is:

1. A grid controlled gas discharge tube including a thermionic cathode, a control electrode, an anode, and a shield electrode, said shield electrode enclosing a pair of enlarged chambers connected by a narrow passage, said cathode being in one of said chambers and said anode in the other chamber, and said control electrode being in said narrow passage.

2. A grid controlled gas discharge tube including a thermionic cathode, a control electrode, an anode, and a shield electrode, said shield elec-

trode enclosing a pair of enlarged chambers connected by a narrow passage, said cathode being in one of said chambers and said anode in the other chamber, and said control electrode being in said narrow passage, said control electrode being in the form of a flattened loop of strip material and oriented with the edges of said strip presented to said cathode and anode.

3. A grid controlled gas discharge tube including a thermionic cathode, a control electrode, an anode, and a shield electrode, said shield electrode enclosing a pair of enlarged chambers connected by a narrow passage, said cathode being in one of said chambers and said anode in the other chamber, and said control electrode being in said narrow passage, said control electrode being in the form of a flattened loop of strip material having the width of said material parallel to the walls of said passage.

4. A grid controlled gas discharge tube including a cathode, a control electrode, and an anode mounted generally along a straight line and a shield electrode enclosing the others of said electrodes, said shield electrode being generally lemniscate in plan with a restricted passage connecting the loops thereof said control electrode being located in said restricted passage.

5. A grid controlled gas discharge tube including a cathode, a control electrode, and an anode mounted generally along a straight line and a shield electrode enclosing the others of said electrodes, said shield electrode being generally lemniscate in plan with a restricted passage connecting the loops thereof, said control electrode being mounted in said passage, said control electrode being in the form of a flattened loop of strip material and oriented with the edges of said strip presented to said cathode and anode.

6. A grid controlled gas discharge tube including a thermionic cathode, a control electrode, and an anode mounted generally along a straight line, and a shield electrode enclosing the others of said electrodes, said shield electrode being generally lemniscate in plan with a restricted passage connecting the loops thereof, said control electrode being mounted in said restricted passage, said shield electrode having an aperture at one end adjacent said anode and said anode blocking said aperture from view of said cathode.

7. A discharge tube including, within a hermetically sealed casing, a cathode, a control electrode, an anode, and a shield electrode, said shield electrode enclosing a pair of enlarged chambers connected by a narrow passage, said cathode being in one of said chambers and said anode in the other chamber, and said control electrode being in said narrow passage.

8. A discharge tube including a hermetically sealed casing containing an ionizable gas, a cathode, a control electrode, an anode, and a shield electrode within said casing, said shield electrode enclosing a pair of enlarged chambers connected by a narrow passage, said cathode being in one of said chambers and said anode in the other chamber, and said control electrode being in said narrow passage, said control electrode being in the form of a flattened loop of strip material and oriented with the edges of said strip presented to said cathode and anode.

9. A gas discharge tube including a hermetically sealed casing containing an ionizable gas, a thermionic cathode, a control electrode, an anode, and a shield electrode within said casing, said shield electrode enclosing a pair of enlarged chambers connected by a narrow passage, said cathode being in one of said chambers and said anode in the other chamber, and said control electrode being in said narrow passage, said control electrode being in the form of a flattened loop of strip material having the width of said material parallel to the walls of said passage.

10. A grid controlled gas discharge tube including a casing containing an ionizable gas, a thermionic cathode, a control electrode, and an anode mounted generally along a straight line within said casing, and a shield electrode enclosing the others of said electrodes, said shield electrode being generally lemniscate in plan with a restricted passage connecting the loops thereof, said control electrode being mounted in said restricted passage.

11. A grid controlled gas discharge tube including a casing containing an ionizable gas, a thermionic cathode, a control electrode, and an anode mounted generally along a straight line within said casing, and a shield electrode enclosing the others of said electrodes, said shield electrode being generally lemniscate in plan with a restricted passage connecting the loops thereof, said control electrode being mounted in said restricted passage, said shield electrode having an aperture at one end adjacent said anode and said anode blocking said aperture from view of said cathode.
